UNITED STATES PATENT OFFICE

GEORGE C. DAVIS, OF DALLAS, TEXAS, ASSIGNOR TO THE B. F. GOODRICH COMPANY, OF NEW YORK, N. Y., A CORPORATION OF NEW YORK

CONVEYER

Application filed February 21, 1929. Serial No. 341,648.

This invention relates to conveyers and more especially to conveyers such as are used in cotton machinery for conveying the cotton to the various working devices thereof.

Conveyers of the character described usually are provided, at intervals throughout their length, with upstanding metal pegs or fingers arranged in transverse rows and secured individually to the belt for urging the cotton into the cotton-working devices. The metal pegs frequently break and fall into moving parts of the machinery and damage the same. They also constitute a fire hazard since, broken metal pegs in contact with moving metal parts frequently produce sparks. Also, considerable labor is required to replace the broken metal pegs.

The chief objects of this invention are to provide a conveyer belt for cotton machinery with pegs of a non-breakable character; to provide for the expeditious mounting and removal of such pegs; to obviate the possibility of damage to machinery from broken pegs; and to eliminate the fire hazard of broken pegs.

Of the accompanying drawings:

Fig. 1 is a fragmentary perspective view of a conveyer embodying my invention in its preferred form, a part being broken away and in section.

Fig. 2 is a section on line 2—2 of Fig. 1.

Fig. 3 is a section of line 3—3 of Fig. 1.

Referring to the drawing, 10 is an endless conveyer belt of leather, rubberized fabric or other suitable material, upon which is mounted at spaced intervals channelled, open-ended cleats or holders 11, 11 disposed transversely of the conveyer and secured thereto by any suitable means such as the rivets 12, 12. The channel of the cleat is defined by side flanges of which the marginal portions 13, 13 are turned toward each other so as to overlie the upper face of the base portion of a peg or finger assembly 14 adapted to be mounted in the channel of the cleat, and said marginal portions 13 are locally depressed at 15, 15 to interfit complementary depressions 16, 16 formed in the base of the peg assembly 14 for yieldingly resisting longitudinal movement of the latter.

The peg assembly 14 preferably comprises a base portion 17 of rigid molded material such as a hard or semi-hard rubber composition, and a plurality of upstanding pegs or fingers 18, 18 of stiff but slightly yielding character. For this purpose I prefer to make the pegs of a strip of rubberized fabric 19 rolled spirally upon itself, the strip being cut obliquely on one end to produce a slightly tapered peg structure, which is secured in the base portion 17 by being molded and vulcanized therein and is provided with a protective surface cover of rubber 20.

The arrangement permits quick and easy mounting or removal of the peg assembly and makes it possible easily to vary the number of peg assemblies on the belt to meet varied operating conditions. The non-metallic character of the pegs obviates the fire hazard heretofore present, and the tough non-breakable structure of the pegs prevents damage and inconvenience resulting from breakage thereof.

The invention is susceptible of modification within the scope of the appended claims.

I claim:

1. The combination of a conveyer belt and a work-engaging member mounted thereupon, said work-engaging member comprising a base portion of relatively hard rubber composition and upstanding pegs integral therewith and comprising a softer rubber composition.

2. A combination as defined in claim 1 in which the pegs are reinforced with fabric which extends into the base portion.

3. The combination of a belt, a transverse cleat secured thereon and defining a recess having overhanging walls, and a bar-like member comprising rubber mounted in said recess and adapted to be mounted therein and removed therefrom by sliding lengthwise thereof, said member being integrally formed with a set of work-engaging fingers of flexible rubber construction.

4. The combination with a distributor belt, of a non-metallic material-engaging pin, a separate metallic mounting by which the pin is secured, and means upon the mounting and

extending through the belt for fastening the mounting thereto.

5. The combination of a conveyer belt, a set of upstanding work-engaging pins thereon each composed essentially of a flexible rubber composition and of finger-like dimensions, and means for holding the base portion of each pin in substantially fixed relation to the belt while leaving the rest of the pin free 10 to be flexed individually.

In witness whereof I have hereunto set my hand this 11th day of February, 1929.

GEO. C. DAVIS.
